Primary Examiner — Cynthia Ramirez(74) *Attorney, Agent, or Firm* — Intellectual Strategies(57) **CLAIM**

The ornamental design for a cart body for a utility cart, as shown and described.

DESCRIPTION

FIG. 1 is a right side view of the cart body for a utility cart showing my new design, showing the handle in an alternate position;

FIG. 2 is a front view thereof;

FIG. 3 is a front bottom perspective view thereof;

FIG. 4 is a front top perspective view thereof;

FIG. 5 is a top perspective view showing the handle in a stored position and the wheels detached; and,

FIG. 6 is a side view thereof.

The broken lines in FIGS. 1-6 show portions of the cart body that are not part of the claimed design. Additional broken lines in FIG. 6 show the environment, which is not part of the claimed design.
